(57) **CLAIM**

The ornamental design for a stand for cocktail shaker kit, as shown and described.

DESCRIPTION

FIG. 1 is a perspective view of the stand for cocktail shaker kit, showing the new design;

FIG. 2 is a front elevational view of the stand for cocktail shaker kit thereof;

FIG. 3 is a top plan view of the stand for cocktail shaker kit thereof;

FIG. 4 is a rear elevational view of the stand for cocktail shaker kit thereof;

FIG. 5 is a bottom plan view of the stand for cocktail shaker kit thereof; and,

FIG. 6 is a right side elevational view of the stand for cocktail shaker kit.

The left side elevation view of the stand for cocktail shaker kit is a mirror image of the stand for cocktail shaker kit illustrated in FIG. 6.
